DESIGN FOR AN ADJUSTABLE LAMP

Edward C. Godfrey, Detroit, Mich.

Application March 26, 1934, Serial No. 51,179

Term of patent 14 years

To all whom it may concern:

Be it known that I, EDWARD C. GODFREY, a citizen of the United States, residing at Detroit, county of Wayne, State of Michigan, have invented a new, original, and ornamental Design for An Adjustable Lamp, of which the following is a specification, reference being had to the accompanying drawing, forming part thereof.

Figure 1 of the drawing illustrates a side ele-

vation of my design for an adjustable lamp in position for use as a table lamp,

Figure 2 of the drawing illustrates a sectional view taken on line 2—2 of Figure 1.

I claim:

The ornamental design for an adjustable lamp as shown.

EDWARD C. GODFREY.
